ELEVATOR CONTROL SYSTEM

Edgar M. Bouton, William A. Clark, and Harold W. Williams, Chicago, Ill., assignors to Westinghouse Electric Elevator Company, Chicago, Ill., a corporation of Illinois

Application October 30, 1935, Serial No. 47,462

8 Claims. (Cl. 172—152)

Our invention relates to control systems and more particularly to systems for controlling the operation of electric elevators, hoists and similar apparatus.

5 In elevator installations embodying variable voltage and other systems of control of the Ward-Leonard type, it has been found uneconomical to keep the operating means or driving motor of the motor-generator set in continuous operation under its own power where the elevator service required is not constant at all times but is intermittent in character.

This will be apparent when it is considered that although the driving motor for the generator in variable voltage control systems must have sufficient capacity for its ordinary operating load, its continuous operation during long periods of time when the elevator is idle, results in lowering the power factor of the supply circuit 20 to an undesirable degree and the no-load losses, when operating under a no-load condition, for a large proportion of its time, become large in proportion to the useful power consumed while the elevator is operating for the purpose of carrying passengers. In some systems of this character, the driving motor may be disconnected from its source of electrical energy and a small auxiliary motor may be used for maintaining the driving motor at its normal speed while it is so disconnected, so that the elevator motor may be placed in operation at any time simply by reconnecting the driving motor to its source of supply.

One object of our invention is to provide a simple and inexpensive means for connecting and disconnecting the driving motor of the above-mentioned systems from its source of supply.

Another object is to provide a system of this character which shall eliminate any flickering of lamps in the elevator system caused by the connecting and disconnecting of the driving motor from its source of electrical energy, when the car is being placed in active condition and inactive condition.

45 It is also an object to provide for eliminating the very high magnetizing peak in the driving motor which usually occurs during the first few cycles of its operation when it is thrown directly on the line while it is running at its normal speed.

For a better understanding of our invention reference may be had to the accompanying drawing, the sole figure of which is a diagrammatic representation of an elevator system embodying our invention.

Referring more particularly to the drawing, we have illustrated an elevator car C as suitably suspended in a hatchway (not shown) by a cable Ca which passes over a hoisting drum D to a counterweight CW.

5 The hoisting drum D may be driven in any suitable manner as by an elevator motor EM having an armature EM' and a separately excited shunt field winding EMF.

A variable voltage system of control may be provided for operating the hoisting motor EM wherein the armature EM' of the hoisting motor is connected in loop circuit with the armature G' of a generator G. The generator G is provided with a series field winding GSF and a separately excited field winding GF.

15 The armature G' of the generator G is suitably driven by means of a main driving motor M. The motor M comprises a squirrel cage rotor M' and a three phase, star connected stator winding MS. The outer leads of the stator winding are connected by a line switch 5 to a suitable source of electrical energy represented by the supply conductors L1, L2 and L3.

A direct current exciter E having a shunt field winding EF and an armature E' is disposed on the shaft of the driving motor for providing a direct current source of excitation for the field winding GF of the generator, the field winding EMF of the elevator hoisting motor, and for operating the various control switches, signal lamps, etc. for the elevator.

25 The direction of the excitation current for the field winding GF of the generator may be suitably controlled by means of an up direction 35 switch 1 and a down direction switch 2. The value of the current supplied to the field winding GF may be controlled by a resistor R4 which may be controlled through a speed relay 3.

A car switch CS is disposed in the car C for controlling the up and down direction switches 1 and 2 for operating the hoisting motor to start and stop the car C and for controlling the operation of the elevator doors (not shown) through the agency of a door closing relay 45. 45 The contact members 45b on the relay 45 are provided for the door operating circuits (not shown).

In elevator installations of the nature shown, a small auxiliary motor AM comprising a rotor AM' and a stator winding AMS is provided for maintaining the driving motor M in constant operation at its normal speed while the car is not being operated. The winding AMS is directly connected to the contact members of the 55

line switch 5 so that closure of the line switch 5 will immediately start the auxiliary motor AM into operation, which will, in turn, cause the driving motor M, the exciter E and the generator 5 G to rotate at normal speed by reason of their being mounted upon the common driving shaft 20. By this system the motor generator set is started and is maintained at its normal speed by the auxiliary motor AM while the car is not 10 in operation so that it will be ready for operation at any instant that the attendant on the car desires to start the car through operating the car switch CS. It will also be apparent that inasmuch as the driving motor M is not yet connected to its source of electrical energy because of open switches in its winding MS, it is not incurring no-load losses and is not affecting the power factor of the supply circuit in any 15 way.

20 In prior systems using an auxiliary motor it has been the practice to connect the driving motor to a source of energy when the car is to be started, by closing a three-pole switch in the main supply line. It has been necessary to use 25 a three-pole switch, because when a two-pole switch is placed in the line of an alternating-current motor, it unbalances the motor to a certain extent, at least to such an extent as to make it unavailable for use in elevator systems 30 where noiseless operation is essential. Also, the prior practice of throwing the motor directly on the line resulted in the occurrence of a very high magnetizing peak in the motor during its first few cycles of operation. This high magnetizing peak causes various disturbances, including flickering of the lamps in the elevator system, by reason of the constant throwing off 35 and on of the motor.

In order to eliminate these difficulties and provide a more economical construction, we have 40 disposed a two-pole switch 11 in the central connectors of the star winding in the driving motor, and have also provided a buffer resistance R1, R2 and R3, controlled by an accelerating 45 switch 10 for the center of the star winding, and have connected these switches in the control system in such manner that an exceedingly smooth operation is secured when the system is placed in operation.

50 A time limit relay 12 is also provided for controlling the operation of the motor accelerating switch 11. The time limit relay is provided with a dashpot 12N to delay its operation for a predetermined period after it is demagnetized.

55 An overload relay 8 is disposed in the circuit leading to the windings AMS, and an overload relay 9 is disposed in the circuit leading to both the windings MS and AMS. The contact members 8a and 9a of the overload relays are disposed in the circuit of the line switch 5 to open that switch and thereby disconnect the motors from their supply circuit when any overload condition occurs in either motor.

60 It is believed that the invention may be best understood by considering the following assumed operation of the system shown.

65 It will be assumed that the system is placed in operation by the car attendant closing a switch 5S which may be disposed in the car C or at 70 any other suitable point. The operation of the switch 5S energizes the line switch 5 by completing a circuit extending from the supply conductor L2 through a protecting fuse 4, switch 5S, the coil of switch 5 and the contact members 8a and 9a of overload relays 8 and 9 to the

75 supply conductor L3. The energization of the line switch 5 causes it to close its contact members 5a, 5b, and 5c, thereby connecting the windings AMS of the auxiliary motor AM to the supply conductors L1, L2 and L3. The energization 10 of the windings AMS causes the motor AM to start in operation, thereby rotating the shaft 21 and causing the motor M, the exciter E and the generator G to operate at their normal rate of 15 rotation.

10 It is understood that the small auxiliary motor AM is so designed in relation to the motor M, the exciter E, and the generator G that it will cause them to operate at their normal speed 15 while the elevator car C is not being operated by the hoisting motor EM. Hence, the driving motor M is always maintained in constant operation at its normal rate of rotation and is always 20 in condition to take up the operation of the elevator car at any instant that the car attendant decides to move the car.

25 The operation of the exciter E causes its voltage to build up to its normal amount, usually approximately 230 volts, whereupon it energizes the time limit relay 12 to close its contact members 12a and open its contact members 12b. The closing of the contact members 12a will permit energization of the driving motor switch 10, but the opening of the contact members 12b will prevent energization of the accelerating 30 switch 11 until the expiration of a predetermined period of time after the time limit relay 12 is deenergized.

35 It will be assumed now that the car attendant decides to move the car upwardly, and, therefore, operates the car switch CS in a counter-clockwise direction. The first movement of the switch CS closes its contact members 13 and 14, thereby energizing the door closing relay 45 to effect the closing of the car door (not shown) 40 by a circuit extending from the supply conductor L+ through conductor 15, contact members 13 and 14, conductor 16, the coil of relay 45 and conductor 17 to the supply conductor L-. The door closing relay is normally so associated with the door operating means (not shown) that it causes the closing of the elevator door (not shown), but, inasmuch as this is old and well known in the art and is not involved in the invention herein set forth, no further illustration or description thereof will be given. However, the relay 45 is provided with an extra 50 set of contact members 45a, which are now closed, and by reason of the closed contact members 12a of the time limit relay 12, effect the 55 energization of the motor switch 10 by a circuit extending from the supply conductor L+ through the contact members 45a, the coil of relay 10 and the closed contact members 12a of relay 12 to the supply conductor L-. 60

65 The energized relay 10 closes its contact members 10a and 10b, thereby inserting the resistors R1, R2 and R3 in the center of the star winding MS and closing that circuit to energize the driving motor M. This circuit extends, one branch 70 from supply conductor L1 through the contact members 5a, the winding 18, resistor R1 and the contact members 10a to the junction point 19, another branch from the conductor L2 through the contact members 5b, one coil of relay 9, 75 the winding 20 and the resistor R2 to the junction point 19, and the other branch from supply conductor L3 through the contact members 5c, one coil of relay 8, winding 21, the resistor R3, the contact members 10b to the junction point 75

18. The closing of this circuit through the buffer resistors R1, R2 and R3 causes the motor M to pick up under its own power.

5 The energization of the relay 10 also causes it to establish a self-holding circuit through its contact members 10c. The closing of the contact members 10d prepares a circuit for energizing the accelerating switch 11.

10 The opening of the contact members 10e of the switch 10 opens the circuit by which the time limit relay 12 was energized, thereby deenergizing that relay. After the expiration of the predetermined time for which the dashpot 12N of the relay 12 is designed, the relay operates to 15 open its contact members 12a and close its contact members 12b. The closing of the contact members 12b completes a circuit for energizing the accelerating switch 11, which circuit extends from the supply conductor L+, through the contact members 45a of relay 45, conductor 28, the contact members 10d of relay 10, the coil of relay 11, and the contact members 12b to the supply conductor L-.

20 The energization of the accelerating switch 11 closes its contact members 11a, 11b and 11c. The closing of the contact members 11c prepares a circuit by which either the up direction switch 1 or the down direction switch 2 may be energized by further operation of the car switch.

25 The closing of the contact members 11a and 11b of the switch 11 short circuits the resistors R1, R2 and R3 in the center of the star windings MS, thereby directly connecting the windings 18, 20, and 21 to the junction point 22 and thus causing the motor M to receive its full supply of energy from the line conductors L1, L2 and L3. The motor M is now operating under its own power, and is operating the generator G through rotation of the shaft 20 to provide 30 operating current for the hoisting motor EM as soon as the field windings GF of the generator are energized by operation of the car switch CS. With this construction, it will be obvious that the motor M, which was being rotated at its 35 normal rate of speed by the auxiliary motor, is now operating under its own power at its normal rate of speed and is ready for operating the motor generator set to effect operation of the car, and that this is effected without causing a 40 high magnetizing peak in the motor M during its first few cycles of operation, thus preventing the flickering of the lamps and any other undesirable effects which would otherwise be caused by throwing the motor directly on its 45 line.

50 It will be assumed now that the door (not shown) has closed, thus closing the door and gate contact members 25 and that the car attendant continues operation of the car switch CS in its counter-clockwise direction, thereby closing its contact members 13 and 23 to effect operation of the up direction switch 1, by a circuit extending from supply conductor L+ through conductor 15, the contact members 13 and 23 of the car switch, the coil of up direction switch 1, the coil of auxiliary switch 7, the door and gate contact members 25 and the contact members 11c of switch 11 to the supply conductor L-.

55 The energization of the auxiliary switch 7 closes its contact members 7a, thus completing an auxiliary circuit for the motor switch 10 and the accelerating switch 11. The auxiliary switch 7 is an interlocking switch which may be employed for various interlocking purposes as in-

60 dicated by the extra contact members 7b. It is shown here for the purpose of illustrating how it may be employed to interlock the circuits for the switches 10 and 11.

65 The energization of the up direction switch 1 closes its contact members 1a and 1b, thereby energizing the field winding GF of the generator G for up direction operation of the car by a circuit extending from supply of conductor L+, through the contact members 1a of switch 1, the 70 winding GF, the contact members 1b of switch 1, and the resistor R4 to the supply conductor L-. The energization of the field winding GF causes the generator G (now being operated by the driving motor M under its own power) to 75 supply current to the hoisting motor EM which in turn operates the hoisting drum D to operate the car C upwardly.

80 It will be assumed now that the car attendant moves the car switch to full "on" position to 20 operate the car at high speed. This action closes the contact members 13 and 26, thus energizing the high-speed relay by a circuit extending from supply conductor L+, through conductor 15, the contact members 13 and 26 of switch CS, 25 the coil of relay 3, the coil of relay 7, the door and gate contact members 25, and the contact members 11c of switch 11 to the supply conductor L-. The energization of the relay 3 30 closes its contact member 3a, thereby short circuiting the resistor R4 in the circuit of the field windings GF of the generator G and thus causing the generator G to supply full current to the hoisting motor EM, thus causing the car C to operate upwardly at its normal high speed. 35

40 By this operation of the system, it is seen that the auxiliary motor AM maintains the driving motor M at its normal speed while the car is out of operation and that as soon as the car attendant operates the car switch to start the car, the driving motor M has its star windings MS connected through the buffer resistors R1, R2 and R3 at the center of its windings MS, and that after the expiration of a predetermined time, the windings MS are directly connected at 45 their center point to cause the motor M to receive full power for operating the car. It will also be seen that this is accomplished by the use of simple and inexpensive two-pole switches and that the buffer resistance prevents any undesirable effects from the operation of connecting the motor M to its supply circuit. 50

55 It will be assumed now that the car attendant, desirous of stopping the car, centers the car switch CS, thereby separating the contact member 13 from the contact members 26, 23, and 14. The separation of the contact members 13 and 26 deenergizes the high-speed relay 3, which opens its contact members 3a, thereby reinserting the resistor R4 in the circuit of the generator field 60 winding GF to decelerate the car from its normal high speed to its landing speed. The separation of the contact members 13 and 23 deenergizes the up direction switch 1, thereby causing it to open its contact members 1a and 1b, thus de- 65 energizing the field winding GF and effecting the stopping of the hoisting motor and the car C. The separation of the contact members 13 and 23 also deenergizes the auxiliary switch 7, 70 thereby causing it to open its contact members 7a in the auxiliary circuit for the switches 10 and 11.

75 The separation of the contact members 13 and 14 of the switch CS deenergizes the motor switch 10 and the accelerating switch 11. The de- 75

energization of the switch 11 opens its contact members 11a and 11b, thereby disconnecting the central portion of the star windings MS from each other. The opening of the contact members 11c will prevent operation of the direction switches until the accelerating switch 11 is again energized.

The opening of the contact members 10a and 10b of the motor switch 10 disconnects the resistors R1 and R3 and opens the circuit in the center of the windings MS, thereby disconnecting the motor M from its source of energy. Inasmuch as the driving motor M no longer operates under its own power, it is now maintained in operation at its normal speed by the auxiliary motor AM while the car is not operating. The rotation of the motor M solely by the auxiliary motor AM prevents any no-load loss on the motor M and also prevents any unfavorable effect on the power factor of the supply system for the motor M while the car is idle.

The opening of the contact members 10c opens the self-holding circuit for the relay 10. The opening of the contact members 10d will prevent energization of the relay 11 until switch 10 is again energized. The closing of the contact members 10e reestablishes the circuit for energizing the time limit relay 12, and that relay immediately resumes its energized position. The energized relay 12 closes its contact members 12a to prepare the circuit of the switch 10 for further operation, and opens its contact members 12b to prevent operation of the accelerating switch 11 until the expiration of a predetermined time after the switch 10 is energized. The system is now ready for the next cycle of operation.

By reason of the foregoing description, it will be seen that we have provided an elevator system having a simple and inexpensive means for connecting the star windings of its driving motor, and that we have also provided a simple and inexpensive system for supplying resistance to the center of the star windings of that motor at the time it is connected for operation under its own power.

Although we have illustrated and described only one system embodying our invention, it is to be understood that modifications thereof and changes therein may be made without departing from the spirit and scope of the invention.

We claim as our invention:

1. In an elevator system for operating a car, a hoisting motor for the car, control means for starting and stopping the hoisting motor, a generator for supplying power to said hoisting motor, a main motor for driving the generator, said main motor having a stator comprising a three-phase star winding, an auxiliary motor for rotating the main motor and the generator when the main motor is not operating under its own power, and means responsive to operation of the control means in starting the hoisting motor for connecting together the center points of said star winding to cause the main motor to operate under its own power when the generator is to operate the elevator motor.

2. In an elevator system for operating a car, a hoisting motor for the car, means for controlling the starting and stopping of the hoisting motor, a generator for supplying power to the hoisting motor, a main motor for driving the generator, said main motor having a stator comprising a star winding, an auxiliary motor for rotating the main motor and the generator while

the main motor is not operating under its own power, means for connecting the outer ends of the star winding to a source of electrical energy, a two pole switch for the center of the star winding, and means responsive to operation of the control means in starting the hoisting motor for operating the two pole switch to connect together the center points of the star winding to cause the main motor to operate under its own power when the generator is to operate the hoisting motor.

3. In an elevator system for operating a car, a hoisting motor for the car, control means for starting and stopping said hoisting motor, a generator for supplying power to said hoisting motor, a main motor for driving the generator, said main motor having a stator including a three-phase star winding, an auxiliary motor for rotating the main motor and the generator when the main motor is not operating under its own power, means for connecting the auxiliary motor and the outer leads of the star winding of the main motor to a source of electrical energy, and means responsive to operation of the control means in starting the hoisting motor for connecting together the center points of said star winding to cause that motor to operate under its own power when the generator is to operate the hoisting motor.

4. In an elevator system for operating a car, a hoisting motor for the car, control means for starting and stopping the hoisting motor, a generator for supplying power to said hoisting motor, a main motor for driving the generator, said main motor having a stator comprising a three-phase star winding, an auxiliary motor for rotating the main motor and the generator when the main motor is not operating under its own power, means for connecting the auxiliary motor and the outer leads of the star winding of the main motor to a source of electrical energy, a plurality of resistors for the center of said star winding, means responsive to operation of the controlling means in starting the hoisting motor for connecting the center points of said star winding through said resistors to cause the main motor to receive a predetermined amount of power from its source of electrical energy.

5. In an elevator system for operating a car, a hoisting motor for the car, control means for starting and stopping the hoisting motor, a generator for supplying power to said hoisting motor, a main motor for driving the generator, said main motor having a stator comprising a three-phase star winding, an auxiliary motor for rotating the main motor and the generator when the main motor is not operating under its own power, means for connecting the auxiliary motor and the outer leads of the star winding of the main motor to a source of electrical energy, a plurality of resistors for the center of said star winding, means responsive to operation of the control means in starting the hoisting motor for connecting the center points of said star winding through said resistors to cause the main motor to receive a predetermined amount of power from its source of electrical energy and for short-circuiting said resistors and directly connecting the center points of said star winding after the expiration of a predetermined period of time to cause the main motor to receive a full supply of power from its source of electrical energy.

6. In an elevator system for operating a car, a hoisting motor for the car, control means for

starting and stopping said hoisting motor, a generator for supplying power to said hoisting motor, an exciter, a main motor for driving the generator and the exciter, said main motor having a stator comprising a three-phase star winding, an auxiliary motor for rotating the main motor, the exciter and the generator when the main motor is not operating under its own power, means for connecting the auxiliary motor and the outer leads of the star winding to a source of electrical energy, a time limit relay disposed to be energized by said exciter, a plurality of resistors associated with the center points of the star winding and means responsive to operation of the control means in starting the hoisting motor for deenergizing the time limit relay and for connecting the resistors in circuit with the center points of said star winding stator to cause the main motor to receive a predetermined amount of power from its source of electrical energy, and means responsive to deenergization of the time limit relay for short circuiting the said resistors and directly connecting together the center points of said star winding to cause the main motor to then receive full power from its source of electrical energy.

7. In an elevator system for operating a car, a hoisting motor for the car, a motor generator set comprising a main motor and a generator for supplying power to the hoisting motor, control means for causing the motor generator set to start and stop the hoisting motor, said main motor having a three-phase star winding stator, an auxiliary motor for rotating the main motor and the generator when the main motor is not operating under its own power, means for connecting the auxiliary motor and the outer lead of the star winding stator of the main motor to a source of electrical energy, a plurality of resistors associated with the center of the star winding stator, and means responsive to opera-

tion of the control means for first connecting said resistors in the center of said star winding stator to cause the main motor to receive a predetermined amount of power from its source of electrical energy, and after the expiration of a predetermined time disconnecting said resistors and directly connecting the center points of the star winding to cause the main motor to then receive full power from its source of electrical energy. 10

8. In an elevator system for operating a car, a hoisting motor for the car, control means for starting and stopping the hoisting motor, a generator for supplying power to the hoisting motor, a main motor for driving the generator, said main motor having a stator comprising a three-phase star winding, an auxiliary motor for rotating the main motor and the generator when the main motor is not operating under its own power, means for connecting the auxiliary motor and the outer leads of the star winding of the main motor to a source of electrical energy, a plurality of resistors for the center of said star winding, a two-pole switch connected in the center of the star winding, a two-pole switch connected in the resistors, and means responsive to operation of the control means in starting the hoisting motor for operating the two-pole switch associated with the resistors to connect the center points of the star winding through the resistors to cause the main motor to receive a predetermined amount of power from its source of electrical energy and for subsequently operating the first named two-pole switch for short circuiting said resistors and for directly connecting the center points of said star winding after a predetermined period of time to cause the main motor to then receive a full supply of power from its source of electrical energy. 20 25 30 35 40
